LAWRENCE E. GOELLER, OF CIRCLEVILLE, OHIO.

BRISTLE-HOLDING DEVICE FOR BRUSHES AND BROOMS.

Application filed January 30, 1928. Serial No. 250,495.

This invention relates to improvements in brush and broom construction, particularly in a means for firmly holding the bristles or fiber which forms the main body portion 5 of the brush, whisk broom or the like in operative position.

An object of this invention is to provide a construction wherein the bristle or fiber portion may be clamped into position, thereby 10 eliminating the need of sewing the folded sections of the fiber together in order to retain its shape and, at the same time, provide the proper flare at the operating end of the brush or broom.

15 A further object of this invention is to provide a brush or broom construction wherein the device may be used as long as the bristle or fiber section retains its efficiency, which is not the case when the 20 bristles are sewed into position, the brush or broom, in this instance, being useful only for the time that the stitches or sewing remains intact.

Another object of this invention is to 25 provide a broom or brush construction in which the bristles or fiber cannot become loosened and detached from the holding member.

Other objects of this invention will appear from the following detailed description 30 of the device and as disclosed in the single sheet of drawings, which is herewith made a part of this application.

In the drawings—

35 Figure 1 illustrates a side elevational view of the brush or broom disclosing its members in assembled relationship.

Figure 2 illustrates a vertical sectional view of Figure 1, omitting one of the clamping members and disclosing the fiber or bristle portion of the brush in position on the retaining band and means for partly holding the retaining band between the clamping members.

45 Figure 3 represents a sectional view of Figure 2 taken along lines 3—3.

Figure 4 illustrates a sectional view disclosing the retaining band and the bristle and fiber portion extending therethrough, 50 together with a looped member on the band for cooperating with a portion of the clamping members.

Figure 5 represents a sectional view of Figure 2 taken along line 5—5.

55 In the modification of this invention as herewith described and claimed, it is pre-

ferred that a plurality of clamping members be provided and made of any suitable material, such as sheet metal, or the like, and formed in such a manner that portions 1 and 2 may be readily used as a handle and sections 3 and 4 as the shank portions of the clamping members, which are adapted to have positioned therebetween bristle or fiber portions 5, made of any suitable material 60 and adapted to extend through a properly formed retaining member 6, made of a material similar to wire and bent into a shape whereby a looped portion 7 is formed through which a shank or rivet 8 may extend. The fiber or bristle element 5 comprises a plurality of strand members which are adapted to be extended through the band member 6 in such a manner that approximately the same amount of the fiber or bristle element will extend on each side of the lower portion 9 of the supporting member 6. After bristle or fiber portions 5 have been properly arranged in cooperation with the supporting band 6, they are positioned 65 between the clamping portions 3 and 4 in such a manner that the shank member 8 of the rivet or tension element 10 passes through the loop 7 connected with the band 6. Another rivet or tension element 11 is 70 then passed through suitable openings in the handle portions 1 and 2. The two tension elements 10 and 11 function to bring the clamping members firmly together, thereby holding the bristles or fiber elements 5 75 in fixed operable position so that they cannot readily become dislodged or separated from each other.

As an aid for holding the fiber strands 5 in fixed relationship to the clamping members, it is preferred that the clamping portions 3 and 4 be formed having downwardly 80 extending curved edges 12 and 13 and inwardly and downwardly protruding portions 14 and 15, which are adapted to be 85 forced into the fiber strands when the clamping members are brought under tension, thereby forming an efficient holding means 90 for the fiber or bristle strands. In order to bring the clamping members in proper alignment and maintain them in that position under tension, it is preferred that one of the 95 clamping portions, including the handle section 1 and shank portion 3, be formed having a straight edge 16, while the cooperating 100 clamping member, comprising the handle section 2 and the shank portion 4 be formed

having an offset or curved section 17 in which the straight edge 15 may be received and firmly held therein.

This invention provides a very efficient brush or broom in which the fiber or bristle portion comprising a plurality of strands is doubled over and positioned between two metal clamping members. The fiber strands, being doubled over between the clamping elements, cannot become dislodged, and the metal clamping portions are constructed in such a manner that they cannot slide sideways and the lap or inwardly extending portion on each clamping member tends to grip the fiber so that it cannot readily be removed, nor can the fiber extend inwardly of the clamping member owing to the manner in which the supporting band is held between the clamping members by the loop and rivet shank. The device herewith described and claimed is practically indestructible. The shape of the clamping members is such as to give the proper flare to the brush, so that the need for sewing any portion of the fibers is entirely eliminated, which tends to make this invention a useful device so long as the fiber strands last. It is well known that, in case of a sewed whisk broom, for instance, its usefulness exists only so long as the stitches or sewing remains intact.

It is to be understood that alterations and substitutions may be made in the embodiment of the invention as defined in the above specifications, including the drawings which are herewith made a part of this application, within the scope of the appended claims without affecting the merits of this invention.

What I claim is:

1. In a brush having folded bristles, means 40 clamping the bristles in position comprising a pair of clamping members, tension members extending through the clamping members, supporting means for the bristles be-

tween the clamping members consisting of a suitably formed band member extending through the bristle fold, means supporting the band between the clamping members consisting of a loop on the band member adapted to receive a tension element. 45

2. In a brush having folded bristles, means 50 clamping the bristles in position comprising a pair of clamping members, tension members extending through the clamping members, supporting means for the bristles between the clamping members consisting of a suitably formed band member extending through the bristle fold, means supporting the band between the clamping members consisting of a loop on the band member adapted to receive a tension element, means 55 for maintaining the clamping members in positive relationship to each other consisting of suitably formed adjacent edges, one of which overlaps the other. 60

3. In a brush having folded bristles, means 65 clamping the bristles in position comprising a pair of clamping members, tension members extending through the clamping members, supporting means for the bristles between the clamping members consisting of a suitably formed band member extending through the bristle fold, means supporting the band between the clamping members. 70 consisting of a loop on the band member adapted to receive a tension element, means 75 for maintaining the clamping members in positive relationship to each other consisting of suitably formed adjacent edges, one of which overlaps the other, and inwardly extending lip portions along the lower edges 80 of the clamping members for firmly gripping the bristle strands. 85

In testimony whereof I affix my signature.

LAWRENCE E. GOELLER.
